US00D598684S

(12) **United States Design Patent**
Stahl

(10) **Patent No.:** **US D598,684 S**
(45) **Date of Patent:** **** Aug. 25, 2009**

(54) **MULTI-LEVEL SLIDING STACKING CONTAINER**

(75) Inventor: **Edward L. Stahl**, Tyler, TX (US)

(73) Assignee: **Norseman Plastics Ltd. (CA)**

(**) Term: **14 Years**

(21) Appl. No.: **29/243,824**

(22) Filed: **Dec. 1, 2005**

(51) **LOC (9) Cl.** **06-04**

(52) **U.S. Cl.** **D6/511**

(58) **Field of Classification Search** **D6/475, D6/510; D3/304, 306, 307, 312; D19/92; 206/505, 513, 203, 503, 557, 561; 211/126.7, 211/194**

See application file for complete search history.

CLAIM

The ornamental design for a multi-level sliding stacking container, as shown and described.

DESCRIPTION

FIG. 1 is a front perspective view of a multi-level sliding and stacking container with a front wall merchandiser window showing my new design;

FIG. 2 is a bottom perspective view thereof;

FIG. 3 is a front view thereof;

FIG. 4 is a back view thereof;

FIG. 5 is a right side view thereof;

FIG. 6 is a right side interior-to-exterior view thereof;

FIG. 7 is a left side view thereof;

FIG. 8 is a top view thereof; and,

FIG. 9 is a bottom view thereof.
